UNITED STATES PATENT OFFICE.

HENRY O. SCHMIDT, OF NEW YORK, N. Y., ASSIGNOR TO THE LANDERS, FRARY & CLARK, OF NEW BRITAIN, CONNECTICUT.

DESIGN FOR A FERRULE.

SPECIFICATION forming part of Design No. 25,268, dated March 24, 1896.

Application filed February 20, 1896. Serial No. 580,135. Term of patent 7 years.

To all whom it may concern:

Be it known that I, HENRY O. SCHMIDT, a citizen of the United States, residing at New York, in the county of New York and State of New York, have invented and produced a new and original Design for a Ferrule, of which the following is a specification, reference being had to the accompanying drawings, in which—

10 Figures 1 and 2 are side elevations of a ferrule for cutlery-handles, showing my design. Fig. 3 is an end view of the same.

The ferrule is of an oval form in cross-section or end view, is ornamented by a beaded band near each end and by a wider band at 15 the middle portion.

The bands near each end are composed of

a series of bead-like ornaments 4, with a narrow plain band 5 immediately upon each side thereof. The middle portion of the ferrule is 20 ornamented by a broader band 6 in relief, composed of leaflets and stems in scroll form on a plain ground, and with a plain space or open field between the same and the end bands 4 5, whereby a pleasing effect is produced. 25

What I claim is—

The design for a ferrule substantially as herein shown and described.

HENRY O. SCHMIDT.
